UNITED STATES PATENT OFFICE.

JOHN J. HOEY, OF PROVIDENCE, RHODE ISLAND.

TENTER-CLIP.

1,272,663.

Specification of Letters Patent. Patented July 16, 1918.

Application filed July 26, 1915. Serial No. 41,817.

To all whom it may concern:

Be it known that I, JOHN J. HOEY, a citizen of the United States, residing at Providence, in the county of Providence, State of Rhode Island, have invented certain new and useful Improvements in Tenter-Clips, of which the following is a specification.

My invention relates to improvements in cloth-clamps for use on tentering-machines employed in finishing textile fabrics. The object of my improvement is to provide means for preventing wear on the jaws of the clamp caused by the vibration and chattering of the upper jaw-member against the lower one after the cloth has been released therefrom.

The invention is fully described in the following specification, illustrated by the accompanying drawings, in which like letters of reference designate like parts.

In the drawings:

Figure 1 is a plan view of a usual type of cloth-clamp, which constitutes one link of the conveyer-chain employed for feeding the cloth through the machine, and illustrating my improvement applied thereto;

Fig. 2 is a side elevation of the same showing the jaw-members in engagement with the cloth;

Fig. 3 is a similar view showing the upper jaw withheld from engagement with the lower one through the operation of my new device.

Referring to the drawings, I have here illustrated a type of cloth-clamp C which is now well known and generally used in the art, but it is to be understood that my improvement is equally well adapted to other forms of clamps and can be applied thereto with but slight modification in its structure. The clamp C here shown comprises the main frame c formed with a base portion b having a lower, projecting jaw-member J and two overhanging arms a, a. Extending through the end of the arms a, a is a shaft or pin p on which is pivoted the upper jaw J'. This is made in the form of a gate-like member having two outer bearings j, j mounted on the ends of the pin p, at the outside of the arms a, a, and a central bearing j' positioned between the two arms. The depending blade-portion j² of the jaw J' is formed somewhat like a hoe and has a relatively sharp, cloth-holding edge j³ which normally bears against the upper surface of the lower jaw J. It is usual to provide the lower jaw J with an

upper face-plate j⁴ which, as here illustrated, is bent down over the front edge of the jaw and fastened thereto by any suitable means, not here shown. The selvage of the cloth x rests on the plate j⁴ and the lower edge of the jaw J' impinges thereupon to bind it in the clamp, see Fig. 2. The jaw J' hangs at an angle to the perpendicular when its lower edge is bearing on the cloth x and consequently the pull of the fabric serves to effect a firm "bite" between the two jaw-members to grip the cloth between them in the usual manner familiar to those versed in the art. A feeler-device or controller d is pivoted on a leg j⁵ of the upper jaw J' and serves as a means for determining the point of engagement of the jaw J' with the cloth relatively to the edge of the latter. As the operation of this device is well known, however, and as it forms no part of the present invention, it will not be further described.

Extending upwardly from the central bearing j' of the jaw J' is a releasing-lever or arm j⁶. The purpose of this is to provide a means for tilting the jaw J' to allow the cloth to enter between it and the lower jaw J, and also to provide for releasing the upper jaw from engagement with the cloth to allow it to be freed from the clamp. The arm j⁶ is operated upon by a member called the "opener" fixedly mounted at each end of the rails in proper position to wipe across its rearmost side which is rounded off at j⁷, see Fig. 1. At either side of the main frame 90 c are ears c', c', etc., which serve as a connecting-means for linking the clamps together. As before explained, each clamp constitutes a link in the endless conveyer-chain, one of which traverses each side-rail 95 of the tentering-frame or machine. The side-rails carry sprocket-wheels at both ends which engage the links to drive the chains in a manner well known to those versed in the art. The clamps engage the selvage of 100 the fabric being treated as they move in one direction on the inside of the rails and upon reaching the end of the frame release the cloth and travel back in the opposite direction to again engage with another length of 105 the material. In this way the fabric is kept continuously in motion through the machine and as it passes from one end of the frame to the other it is stretched across its breadth, smoothed out and otherwise treated 110 to impart the desired finish to its surface. It is usual in machines of this class to pro-

vide, besides the continuous feeding motion of the chains, an additional back-and-forth or reciprocating movement of the side-rails so that the cloth is stretched with a criss-cross jerking action which tends to smooth out the wrinkles and open up the texture. This movement of the side-rails causes more or less thumping and pounding in the various parts of the machine and sets up considerable vibration in the cloth-clamps as they pass along the outside of the rails after being freed from the fabric. After the upper jaw J' has been once tilted back to release the cloth it swings down again under the action of gravity until its lower edge meets the upper face of the plate j^4 . Now, as the clamp jumps and chatters, due to the vibration of the side-rails, this sets up a vibration of the jaw J' and its lower edge j^3 will chatter up and down against the plate j^4 . This undue movement of the jaw J' soon acts to wear a groove in the plate j^4 and, after the latter becomes uneven, the clamp will not grip the cloth properly. As the jaws J' must be made relatively stanch and heavy, to resist the strain imposed upon them by strong materials, the force of its lower edge striking against the plate j^4 is considerable and the surface of the plate will become very badly worn within a comparatively short time. After the plate has become worn and grooved to such an extent that it does not hold the cloth firmly it must either be filed down to a smooth surface or else replaced by a new one. Each conveyer-chain is generally composed of several hundred links or clamps and these must be taken apart in order to repair them. It will therefore be seen that it is a very considerable task to replace and refit the jaw-plates on the chains of one machine and calls for the expenditure of a great deal of time and money. It is the purpose of the present invention to entirely obviate this unnecessary wear of the upper jaw upon the lower one and I accomplish this result in the following manner:

Referring to Fig. 3, my improvement consists essentially in providing a detent-means to hold the movable jaw J' in its raised position after it has been released from the cloth. As here shown I employ a lever D which engages suitable detents on the jaw after the latter has been opened. The lever D is preferably formed of sheet-metal with two ears d' , d' bent downwardly at right-angles to its main portion and adapted to receive the pivot pins d^2 , d^2 which are driven into the sides of the arms a , a . The rear end of the lever D carries a downwardly-extending pin d^3 which is engaged by the end of a coiled spring E . The opposite end of the spring E bears against a portion b' of the base b of the clamp and is held in position by a pin e driven into the base. The forward part of the lever D is of bifurcated

form having two legs d^4 , d^4 which straddle the arm j^6 of the jaw J' . The ends of the legs d^4 are preferably bent or curved over in the arcuate portions d^5 having their under, concave faces adapted to engage the rounded edges of the lugs j^8 , j^8 which project from both sides of the arm j^6 . With the jaw J' in its closed position, as illustrated in Fig. 2, the legs d^4 rest on the upper faces of the lugs j^8 and have a tendency to maintain the jaw J' from undue movement while its lower edge is bearing on the cloth x . When the jaw J' is tilted into the position illustrated in Fig. 3, the ends of the legs d^4 ride over the upper faces of the lugs j^8 and engage the sides thereof to hold the jaw in its raised position. It will be noted that the end of each of the legs d^4 is rounded off at d^6 to provide a sort of cam-face which assists in moving the jaw to its retracted position and also gives a smoother and easier action between the engaging faces. The rearward movement of the jaw J' is limited by the contact of the upper edge j^9 of its blade j^2 with the arms a , a as shown in Fig. 3. The operation of the complete device is as follows:

The clamps C travel along the inside of the two side-rails of the tentering-machine with their jaws J , J' gripping the selvage of the cloth x as illustrated in Fig. 2. As each clamp reaches the end of the rail the arm j^6 of its upper jaw J' is engaged by the fixed "opener" and the jaw is raised or opened to the position illustrated in Fig. 3 to release the cloth. During the tilting of the jaw J' , as above described, the ends of the legs d^4 of the detent-lever D ride across the upper edges of the lugs j^8 on the arm j^6 and the action of the spring E on the opposite end of said lever causes them to slide down into engagement with the sides of the lugs. This engagement acts to retain the jaw J' in its retracted position, as illustrated in Fig. 3, and prevents its blade-portion j^2 from dropping back into position to bear on the jaw J . In this way the sharp edge j^3 of the jaw J' is prevented from jumping up and down and vibrating against the plate j^4 , and consequently all unnecessary wear on the surface of the plate is obviated. The clamps, as they become freed from the cloth at one end of the machine, travel along the outside of the rails to the opposite end where they turn on the chain-sprockets and again travel up the inside of the rails. Just before they pass into position to engage the cloth the rear end of the detent-lever D is engaged by a suitable means, such, for instance, as a cam or roller, not here shown, and this acts to tilt the lever to raise the ends of its legs d^4 from the lugs j^8 . Through this action the jaw J' is released to allow it to swing down into position to engage with the cloth x , as shown in Fig. 3.

Fig. 2, and this engagement is effected as soon as the clamp comes around into place on the inside of the rail. The jaw J' now remains in this position until the clamp 5 reaches the opposite end of the machine when it is again released by the "opener".

It will be seen that my improvement provides a simple and effective means for restraining the upper, movable jaw of the 10 clamp from undue vibration, after it has been released from the cloth, and for holding its edge out of engagement with the lower-jaw of the clamp so that all unnecessary wear on these parts is eliminated. For 15 this reason both the jaw J' itself and the lower face-plate j^a are rendered more durable and hence a considerable saving is made in the cost of repairs. Besides this, the usual "opener", provided for opening the jaw before 20 the clamp comes into engagement with the cloth, can be dispensed with and, therefore, about half the wear on the opener-arm j^a is eliminated. It is also called to attention that my new detent-means can be applied to clamps already in use at a very 25 slight expense; and when so applied will greatly increase the durability of the parts thereof.

Various modifications might be made in 30 the form and structure of my new device without departing from the spirit or scope of the invention; therefore, without limiting myself to the exact construction shown and described, what I claim is:—

35 1. In a cloth-clamp for tentering- or like machines, the combination with the main frame thereof having a base providing a lower fixed jaw and arms overhanging the top of said base, of an upper movable jaw pivoted to the arms on the frame to adapt its lower end to swing into engagement with the fixed jaw, detent-lugs projecting vertically upwardly from the pivot of the movable jaw, a detent-lever pivoted on the top 40 of the arms of the frame and formed with curved ends adapted to normally ride on the ends of the lugs on the movable jaw, and a spring to operate the detent-lever when the movable jaw is swung into open position 45 to cause the ends of the lever to engage the

sides of the lugs to hold the jaw from closing.

2. In a cloth-clamp for tentering-machines, the combination with a main frame having a relatively flat base forming a lower 55 jaw and arms overhanging the top of the base, of a rod extending through bearings in the arms on the frame, an upper movable jaw pivoted on said rod and formed with its depending portion adapted to engage with 60 the lower jaw of the frame, detent-lugs having rounded ends extending upwardly from the pivot of the movable jaw, a detent-lever having ears pivoted to the sides of the arms on the frame and legs extending longitudinally of said arms to bear against the lugs on the movable jaw, and a spring acting 65 against the rear end of the detent-lever to cause its forward end to engage the sides of the lugs on the movable jaw when the latter 70 is rocked to swing its lower end away from the fixed jaw.

3. In a cloth-clamp for tentering-machines, the combination with a frame having a relatively flat base forming a lower fixed jaw 75 and arms overhanging said base, of a movable jaw-member having hubs pivoted to the arms on the frame to adapt its lower edge to coöperate with the fixed jaw on the frame and also formed with an arm extending upwardly between the frame-arms, vertically-extending lugs on the sides of the central arm of the lower jaw, a relatively flat detent-lever having ears pivoted to the sides of the arms on the frame and formed with two 80 legs straddling the central arm on the movable jaw with their ends adapted to bear against the upper ends of the lugs thereon, and a spring operating on the opposite end of said lever to cause the arms to ride down 85 against the sides of the lugs when the movable jaw is tilted to withdraw its lower end from engagement with the fixed jaw.

In testimony whereof I affix my signature in presence of two witnesses.

JOHN J. HOEY.
